(57) CLAIM

The ornamental design for a set top box with server, as shown and described.

DESCRIPTION

FIG. 1 is the front/right-side/top perspective view of a set top box with server showing our new design;
FIG. 2 is the front elevational view thereof;
FIG. 3 is the rear elevational view thereof;
FIG. 4 is the left-side elevational view thereof;
FIG. 5 is the right-side elevational view thereof;
FIG. 6 is the top-side plan view thereof;
FIG. 7 is the bottom-side plan view thereof; and,
FIG. 8 illustrates the server is apart from the set top box with server.
The broken lines shown in the drawings show unclaimed subject matter only and form no part of the claimed design.
